PULVERIZED-FUEL BURNER

Robert Jean Charles Boudrant, Paris, France,
assignor to Société d'Électricité de Paris, Paris,
France, a joint-stock company of France

Application March 10, 1937, Serial No. 130,170
In France March 25, 1936

3 Claims. (Cl. 110—104)

This invention relates to pulverized-fuel burners and has for its object to ensure the combustion of the pulverized fuel as completely and rapidly as possible.

It is known that in burners of large dimensions, very great difficulties are encountered in obtaining a homogeneous mixture of air and coal. There occurs either an excessive elongation of the flame or considerable loss by solid unburnt particles resulting from incomplete combustion.

The invention provides for obtaining, with a burner of large rating, a fuel-comburent jet as homogeneous as possible; it consists in dividing the flow of primary air and fuel into several equal streams or sections and interposing between them alternate streams of secondary air in suitable proportion.

In order to secure at the mouth of the burner the desired mixture between the streams of secondary air and those of primary air and fuel, the latter are injected, not in a continuous manner, but intermittently in order to produce pulsations of high frequency.

Upon the accompanying drawings to which reference is made in the subsequent description, there has been represented by way of example, one form of construction of the improved compound burner.

Fig. 1 shows in its upper half a sectional elevation along the axis of the apparatus and in its lower half an elevation, only the casing for secondary air being in section.

Fig. 2 is a front view of the apparatus, from which the rotary mixer has been removed.

Figs. 3 and 4 are half sections taken respectively along the lines 3—3 and 4—4 of Fig. 1.

In all these figures the same reference numerals designate the same parts or elements.

Within the pipe supplying pulverized coal and primary air is mounted a rotary mixer 1, Fig. 1, preferably of the kind described in my pending application Serial No. 102,215, filed Sept. 23, 1936, which ensures thorough mingling of the primary air and fuel mixture before its entrance to a divider 2.

The divider 2, Figs. 1, 2 and 3, is composed of iron or steel walls resting against one another in pairs, forming a star with any suitable number of branches; these walls constitute the flanks of ducts 3, Figs. 3 and 4, for the passage of the primary air and fuel current, the walls resting at their central parts upon a hollow cone 4, Figs. 1 and 3, and being closed at the periphery so as to form fluid-tight conduits open only at their two ends.

The ducts 3 each maintain an approximately constant cross-sectional area as far as the mouth of the burner, but they increase in radial height while decreasing in angular width regularly from the entrance to the exit. The free spaces or channels 5, Figs. 1, 3 and 4, thus provided between adjacent ducts 3, have a cross-sectional area which is nil at the entrance to the divider and maximum at the burner outlet.

These channels 5 are all in communication at their periphery with the chamber 6, Figs. 1 and 3, constituting the secondary air casing, and at their ends they open out into the combustion space.

Within the opening into the combustion space, two angularly adjustable shutters 7, Figs. 1 and 15 4, are placed in each channel 5; they allow regulation both of the supply of secondary air and of the angular relation of the streams of secondary air towards the streams of primary air and fuel.

All the shutters 7 can be operated simultaneously by a device such as represented at 8, Figs. 1 and 2, or any other analogous device.

The hollow central cone 4 is provided with an adjustable register 9, Figs. 1 and 4, controlled by a hand wheel 10, Figs. 1 and 2, from the exterior 25 of the burner.

This register allows of uncovering more or less a plurality of slots 11, Figs. 1 and 4, for communication between the secondary air casing 6 and the interior of the central cone 4 so as to be able to admit more or less air to the very centre of the flame and thereby to lengthen or shorten the flame according to the nature of the coal being burnt or the needs of combustion.

It will be readily understood that upon the passage of one of the blades of the second or downstream screw rotor of the rotary mixer 1 in front of one of the ports or apertures of the divider 2, a supplementary loss of head will be set up at the entrance to this aperture; since this operation takes place three or four times for each revolution of the mixer 1 according as the rotor in question is fitted with three or with four blades, there is produced a high frequency pulsatory action for the injection of the primary air 45 and fuel current.

This pulsation is extremely favorable to the mixing of the primary and secondary currents at the exit from the burner and it improves the combustion to a considerable extent.

In large burners, it is advantageous to increase the pulsating effect by causing the rotor blades or the rotor spindle to carry a set of flat shutters (not shown in the drawings) having the shape of one of the divider ports, the plane containing 55

these shutters being perpendicular to the common axis of the rotary mixer.

- 5 The burner described above is of the radiant type, possessing an axis of symmetry, but it is naturally permissible without departing from the scope of the invention, to arrange the component parts of this burner in a different way so as to produce modifications operating practically in the same way.
- 10 The number of ducts is a function of the dimensions of the burner; by way of illustration, it is eight in the drawings. It is advantageous to increase that number in the case of a very large burner.

15 What I claim is:

1. In a pulverized-fuel burner, a pipe supplying a current of primary air containing pulverized fuel, two rotary mixing devices in said pipe, each of said mixing devices comprising a helically bladed rotor adapted for revolving by said current, one of said rotors having right handed blades and the other left handed blades, and the two rotors being arranged coaxially, one immediately behind the other, said mixing devices adapted to homogenize the mixture of air and fuel in said current, means for dividing said homogenized current into a plurality of streams, said dividing means including a plurality of substantially equal ports, said mixing devices having 20 blades rotating in proximity to the ports of said dividing means, a plurality of ducts conveying said streams, said ducts being spaced around the axis of said pipe and increasing in radial height while decreasing in angular width towards the 25 burner mouth, a casing for supply of secondary air, said casing being in communication with the spaces between said ducts, and means for regulating the mixture of secondary air from said spaces with said primary air streams at the 30 burner mouth.

2. In a pulverized fuel burner, a pipe for supplying a current of primary air containing pulverized fuel, means for rendering said current substantially homogeneous, means for dividing said homogenized current into a plurality of streams, a plurality of ducts conveying said streams, said ducts being spaced around the axis of said pipe and increasing in radial height while decreasing in angular width towards the burner mouth, a hollow open-ended cone aligned with 5 said axis and forming a divergent core to said ducts, the base of said cone being open in the direction of discharge from said ducts, a casing for supply of secondary air, said casing being in communication with the spaces between said ducts, said cone having a plurality of apertures in communication with the spaces between said ducts, means for regulating the flow of secondary air from said spaces through said slots into said cone, and means for regulating the mixture of 10 secondary air from the discharge ends of said spaces with said primary air streams at the burner mouth.

3. A pulverized fuel burner, comprising a pipe supplying a current of primary air containing 20 pulverized fuel, means for homogenizing the mixture of air and fuel in said current, means for dividing said current into a plurality of substantially homogeneous streams spaced about an axis 25 in line with the axis of said pipe, means located adjacent to said dividing means for setting up pulsating effects in said streams, means for interposing streams of secondary air between said spaced streams, and controllable means for mixing said streams, said controllable means providing for regulation of the speed and direction of 30 said secondary air independently of its amount.

ROBERT JEAN CHARLES BOUDRANT. 40
